DOOR LOCK

Crayton J. Dials, Oakland, Calif.

Application October 16, 1937, Serial No. 169,486

6 Claims. (Cl. 70—149)

This invention relates to door locks.

It is the principal object of my present invention to provide an improved lock structure for doors which is pick and tamper proof and in which the retraction of the bolt is controlled by air pressure actuated means rendered effective only by means of a proper key.

In practicing my invention I provide a lock structure having a bolt operable by turning of an oscillatory element. The latter is associated with an operating knob which may be effectively connected therewith by engagement of a clutch or disconnected therefrom by disengagement of the clutch. A tumbler is provided for latching the clutch in disengaged condition. This tumbler may be released to cause engagement of the clutch by air pressure means rendered effective by the use of a proper key.

One form which the invention may assume is exemplified in the following description and illustrated by way of example in the accompanying drawings, in which:

Fig. 1 is a view in central longitudinal section through a lock embodying the preferred form of my invention.

Fig. 2 is a similar view with the operating parts in position rendering the exterior knob or handle effective.

Fig. 3 is a view similar to Fig. 1 showing the operating parts in position they assume upon mechanical release of the tumbler.

Fig. 4 is a central transverse section through the lock.

Figs. 5 and 6 are fragmentary views showing the mechanism for latching the push button of the inner knob.

Referring more particularly to the accompanying drawings, 9 indicates a lock for use on doors where it is desired that key means may be required to gain entrance.

In the drawings, 10 indicates a door through which is bored a circular opening 11 within which the lock is assembled. A bored hole 12 is drilled into the bolt edge of the door perpendicularly to the opening 11 and intersecting the same to receive the bolt of the lock as will be described. It is apparent from this that to condition the door for reception of the lock it is only necessary to bore the two holes 11 and 12 in the door and no mortising or other time consuming labor is required.

The door lock includes inner and outer escutcheon plates 14 and 15 of an exterior diameter greater than the bored hole 11 and shouldered as at 16 so as to securely rest within and align with

the opening 11. The escutcheon plates 14 and 15 are secured together and to the door by screws 16 accessible from the interior side of the door only.

The outer escutcheon plate is centrally bored as at 17 and the inner escutcheon plate is centrally bored as at 18. Both plates are counter-bored as at 19 at their interior sides to rotatably receive a bolt retracting cylinder 20.

At the inner side of the door the retracting cylinder 20 is formed with a co-axially extending knob shank 21 which projects through the bore 18 of the escutcheon plate 14 and is fitted at its extremity with an inner handle or knob 22 which is securely fixed thereto.

Centrally between its ends and within the opening 11 the retracting cylinder 20 is formed with a pair of spaced annular flanges 23 circum-scribing the exterior thereof. Loosely positioned between these flanges and partially embracing the retracting cylinder 20 is a bolt yoke 24 which is connected to the lock bolt 25 of the lock as shown in Figure 3 of the drawings. Cooperating lugs 26 on the yoke 24 and one flange 23 provide the means of retracting the bolt 25 regardless of the direction of turning of the retracting cylinder 20.

As will be seen from Figure 3, a spring 26 normally tends to maintain the bolt projected in a latching position.

Thus from the foregoing, it is obvious that at all times the bolt 25 may be retracted by manipulation of the inner knob or handle 22.

It is, of course, required in a lock of this character that retracting of the bolt from the exterior side of the door be optionally key-controlled or not. This is accomplished in this instance providing a knob sleeve 27 rotatably mounted in the bore 17 of the exterior escutcheon plate 15.

At its outer end the knob sleeve 27 is fitted with a fixed knob or handle 28 spaced outwardly from the plate 15. At its inner end and within the counterbore 19 of the plate 15 the knob sleeve 27 is formed with a clutch disc 29 rotatably received in the contiguous end of the retracting cylinder 20.

When the lock is in condition where a key must be employed to enable retraction of the bolt 25, the sleeve is freely rotatable relative to the retracting cylinder 20 and the escutcheon plate 15 so that operation of the knob 28 and sleeve 27 at the exterior of the door will be ineffective in retracting the bolt 25.

For rendering the knob 28 and sleeve 27 effective in retracting the bolt 25 I have provided a tumbler barrel 30 reciprocably mounted in the

knob sleeve 27 with its inner end reciprocably but non-rotatably mounted in a tumbler cylinder 31. The latter in turn is reciprocably mounted in the retracting cylinder 20.

5 The tumbler cylinder 31 is formed with a coaxially extending button shaft 32 reciprocably extending axially through the knob shank 21 and fitted at its end with a button 33 by means of which the tumbler cylinder 31 may be moved axially in the retracting cylinder for rendering the outer knob 28 effective or ineffective in regard to bolt retraction as will be described.

10 It will be noticed that the inner end of the tumbler barrel 30 projects into the open end of the bore 34 of the tumbler cylinder 31 and that the opposite end of the bore 34 is closed. A spring 35 is positioned between the end of the tumbler barrel 30 and the closed end of the bore 34 normally maintaining a spacing therebetween to form a 15 vacuum chamber 34a. The spring 35 also acts as will be described and under certain circumstances to move the tumbler barrel outwardly and in so doing render the outer knob 28 and its sleeve 27 effective in turning the retracting cylinder 20 to 20 retract the bolt 25.

25 The tumbler barrel is formed with a transverse bore 36 extending inwardly from one side thereof but terminating short of the opposite side as shown in Figures 1 and 2. Snugly but slidably 30 fitted into this bore is a tumbler 37. A light spring 38 normally tends to project this tumbler from the side of the tumbler barrel into engagement with a tumbler socket 39 formed in the side of the bore 34 of the tumbler cylinder to 35 maintain the tumbler barrel in retracted position as shown in Figure 1. Such engagement, however, permits a certain amount of inward movement of the tumbler barrel toward the closed end of the bore 34.

40 It should be stated that by moving the tumbler barrel inwardly into close proximity with the closed end of the bore and then releasing it so that the spring rapidly moves it outwardly, a 45 vacuum or suction is created which is utilized to retract the tumbler 37 from engagement with the socket 39. Such disengagement enables the tumbler barrel to continue to move outwardly and condition the mechanism so that the outer knob 28 and its sleeve 27 will be effective in retracting the bolt 25.

50 The vacuum or suction created as described will produce a suction through a passageway 40 which extends longitudinally through the tumbler barrel 30 communicating at one end with the 55 chamber 34a and at the other end with the interior of the key socket 41 formed in the outer end of the tumbler barrel. This socket removably receives a key 42.

50 A second passageway 43 is formed in the tumbler barrel 30 and communicates at one end with the inner end of the tumbler bore 36 and at the other end with the key socket 41. The key is so formed that when inserted into the socket it shuts off the communication between the atmosphere and the passageways 40 and 43 and establishes a direct communication between these passageways. Therefore, when suction is created in the chamber 34a this will create a reduced pressure in the inner end of the tumbler bore 36 through 65 the passageways 40 and 43 and cause retraction of the tumbler 37 and release of the tumbler barrel. The latter will then move outwardly with the before stated results.

70 To clutch the knob 28 and sleeve 27 to the 75 retractor cylinder 20, a movable clutch plate

45 is provided which is slidable mounted on the sleeve 27 and slidable but non-rotatably mounted within the retracting cylinder 20. A pin 46 secured to the clutch plate 45 and engaged with a keyway 47 in the retracting cylinder prevents 5 relative rotation between the plate 45 and the cylinder 20. Consequently, when the lugs on the clutch plate 45 are engaged with the lugs on the clutch plate 29 (which is fixed to the knob sleeve 27) the knob 28 and its sleeve 27 will be clutched to the retracting cylinder 20 and effective to retract the bolt.

10 A spring 48 normally maintains the clutch disengaged, but when the tumbler barrel moves outwardly an annular shoulder 49 thereon engages 15 the clutch plate 45 and moves it and its lugs into engagement with the lugs of clutch plate 29.

15 The endwise outward movement of the tumbler barrel is limited by engagement of a pin 50 fixed to the barrel engaging a keyway 51 formed in 20 the tumbler cylinder 31. This engagement also prevents relative rotation between the barrel 30 and the cylinder 31.

25 For conditioning the mechanism to change the knob and sleeve from effective to ineffective condition, it is merely necessary to press the button 33 inwardly which moves the tumbler cylinder inwardly relative to the tumbler barrel sufficiently to re-engage the tumbler socket 39 with the tumbler. When released, the button will be returned 30 to normal position returning the tumbler cylinder 31 and the tumbler barrel 30 with it, by means of the spring 52.

35 To render the outer knob 28 and its sleeve 27 effective from the inside of the door, it is only necessary to pull outwardly on the button 33 which causes a tumbler depressor 53 in the tumbler socket 39 to ride on a cam shoulder 54 which moves the depressor inwardly. Such movement moves the tumbler inwardly and releases the tumbler barrel allowing it to move outwardly, as previously described, and clutch the outer knob sleeve 27 to the retracting cylinder.

40 I wish to point out that if the proper key is not used the bolt cannot be retracted due to the fact 45 that the vacuum or suction will be equalized at both ends of the tumbler 37 due to the passages 55 and 56. Obviously vacuum or suction applied to the open key socket would be ineffective to render the knob 28 and its sleeve 37 effective in 50 retracting the bolt 25.

45 To prevent mechanically gripping the tumbler barrel and pulling it and the cylinder 31 outwardly, the shank 21 is formed with a bayonet slot 60 and the shaft 32 with a pin 61. When 55 the shaft is turned to place the pin 61 out of register with the longitudinal portion 60a of the slot 60, the barrel 30 and cylinder 31 cannot be pulled endwise to effect clutching of the sleeve 27 to the retracting cylinder 20.

60 In operation of the lock it is constructed and assembled as shown in the drawings and as previously described herein. Assuming that the mechanism of the lock is in the condition shown in Figure 1, it is obvious that by turning the 65 interior handle 22 that the retracting cylinder 20 will be turned and consequently the bolt 25 will be retracted. Also it is obvious that inasmuch as the movable clutch plate 45 is out of engagement with the clutch plate 29 on the knob sleeve 27 70 that rotation of the knob will be independent of the retracting cylinder of the bolt 25.

75 If it is desired to render the outer knob 28 effective from the inner side of the door, it is only necessary to exert a pull on the button 33. 75

This, as previously described, will move the tumbler cylinder 31 sufficiently so that the cam shoulder 54 will depress the tumbler depressor sufficiently to disengage the tumbler 37 from the tumbler socket 39. Immediately that this disengagement takes place, the spring in the chamber 34a will move the tumbler barrel endwise in a direction causing engagement of the movable clutch plate 45 with the clutch plate 29 on the knob sleeve 30. Such engagement clutching the knob sleeve 27 to the bolt retracting cylinder 20 so that the knob 28 and its sleeve 27 will be effective in retracting the bolt 25.

To disconnect the sleeve 27 from the bolt retracting cylinder 20, it is only necessary to press inwardly on the button 33 which will place the tumbler socket 39 in register with the tumbler 27 so that upon release of the button 33 the spring 52 will move the tumbler barrel to a position disengaging the movable clutch plate from the clutch plate 29.

If it is then desired to retract the bolt by operation of the exterior knob at exterior of the door, the key 42 is placed in the key socket and pressed inwardly so as to move the inner end of the tumbler barrel 30 toward the closed end of the bore 34 and then release the tumbler barrel so that it moves in the opposite direction. This, as previously described, will create a suction or vacuum through the passageway 41, thence through the key 42 and passageway 43 of the inner end to the tumbler bore 36. This causes the tumbler 37 to move inwardly and disengage from the socket 39 so that the spring 35 in the chamber 34a will move the tumbler barrel outwardly to engage the movable clutch plate with the clutch plate 39 on the knob sleeve 27, clutching the latter to the retracting cylinder. To again render the outer knob 28 and its sleeve 40 27 ineffective, it is only necessary to depress the button 33, as previously described. It should be stated that when the key 42 is used to press the barrel inwardly, the latter will move relatively to the cylinder 31, due to the fact that the spring 45 in the chamber 34a is lighter than the spring 65 which is positioned between the adjacent ends of the tumbler cylinder 31 and the retracting cylinder 20.

As before stated, by turning the button 33, to place the pin 61 out of register with the slot 60a, no external mechanical force can be employed to move the tumbler barrel and thus "pick" the lock. Likewise if an improper key is employed, suction will be equalized on both 55 sides of the tumbler 37, as previously described, so that the bolt may not be operated from the exterior side of the door except with the use of the proper key.

It is obvious that almost innumerable combinations of ports may be arranged in the key socket so that no two locks may be opened by the same key.

While I have shown the preferred form of my lock, I wish it to be understood that various changes may be made therein by those skilled in the art without departing from the spirit of the invention as defined in the appended claims.

I claim:

1. A lock of the character described, comprising a bolt, a rotatable element connected therewith for retracting the same, a turnable knob shaft at one side of the lock, clutch means normally tending to engage and connect the knob shaft to the turnable element, a tumbler for latching said clutch means in disengaged con-

dition, and manually operative pneumatic means associated with the tumbler to set up a suction influence contiguous thereto to move the same from latching position.

2. A lock of the character described comprising a bolt, a rotatable element connected therewith for retracting the same, a turnable knob shaft at one side of the lock, clutch means normally tending to engage and connect the knob shaft to the turnable element, a tumbler for latching said clutch means in disengaged condition, and manually operative pneumatic means associated with the tumbler to set up a suction influence contiguous thereto to move the same from latching position, and manually operative means at the side of the lock opposite the knob shaft for disengaging the clutch means, said last named means being capable of manual operation to mechanically disengage said tumbler from latching position and enable engagement of the clutch means.

3. A lock of the character described comprising a bolt, a rotatable element connected therewith for retracting the same, a turnable knob shaft at one side of the lock, clutch means normally tending to engage and connect the knob shaft to the turnable element, a tumbler for latching said clutch means in disengaged condition, and key controlled manually operative pneumatic means associated with the tumbler to create a suction influence contiguous thereto capable of withdrawing the same from latching position.

4. A lock of the character described comprising a bolt, a rotatable element connected therewith for retracting the same, a turnable knob shaft at one side of the lock, clutch means normally tending to engage and connect the knob shaft to the turnable element, a tumbler for latching said clutch means in disengaged condition, and manually operative pneumatic means associated with the tumbler to set up a suction influence contiguous thereto to move the same from latching position, and a second knob shaft at the opposite side of the lock relatively fixed to the rotatable element.

5. A lock of the character described comprising a bolt, a rotatable element connected therewith for retracting the same, a turnable knob shaft at one side of the lock, clutch means normally tending to engage and connect the knob shaft to the turnable element, a tumbler for latching said clutch means in disengaged condition, key controlled and manually operative pneumatic means disposed partially within the knob shaft and operatively associated with the tumbler to create a suction influence at one end thereof capable of causing withdrawal of the tumbler from latching position.

6. A lock of the character described, comprising a bolt, a rotatable element connected therewith for retracting the same, a turnable knob shaft at one side of the lock, clutch means normally tending to engage and connect the knob shaft to the turnable element, a tumbler for latching said clutch means in disengaged condition, manually operative pneumatic means for creating a suction influence, normally ineffective air conducting means rendered effective by means of a key for causing the suction influence so produced to effect a low pressure area at one end of the tumbler to cause the same to move to an unlatched position.
